(57) **CLAIM**

The ornamental design for an enclosure of a voice assistant device, as shown and described.

DESCRIPTION

FIG. 1 is a front perspective view of an enclosure for a voice assistant device in accordance with a first embodiment of the invention;

FIG. 2 is a top perspective view of the embodiment in FIG. 1;

FIG. 3 is a right perspective view of the embodiment in FIG. 1;

FIG. 4 is a bottom perspective view of the embodiment in FIG. 1;

FIG. 5 is a front perspective view of an enclosure for a voice assistant device in accordance with a second embodiment of the invention;

FIG. 6 is a top perspective view of the embodiment in FIG. 5;

FIG. 7 is a right perspective view of the embodiment in FIG. 5;

FIG. 8 is a bottom perspective view of the embodiment in FIG. 5;

FIG. 9 is a front perspective view of an enclosure for a voice assistant device in accordance with a third embodiment of the invention;

FIG. 10 is a top perspective view of the embodiment in FIG. 9;

FIG. 11 is a right perspective view of the embodiment in FIG. 9; and,

FIG. 12 is a bottom perspective view of the embodiment in FIG. 9.
